LASTING MACHINE

Philip E. Burby, Beverly, Mass., assignor to United
Shoe Machinery Corporation, Flemington, N. J.,
a corporation of New Jersey

Application September 18, 1942, Serial No. 458,850

35 Claims. (Cl. 12—14)

This invention relates to lasting machines, and is herein illustrated as applied to a power-operated toe-lasting machine which, except as hereininafter noted, is constructed generally as disclosed in United States Letters Patent No. 2,160,846, granted on June 6, 1939, on an application of F. C. Eastman's and A. F. Pym's. It is to be understood, however, that in various novel aspects the invention is not limited to the illustrated embodiment.

The machine shown in the above-mentioned Letters Patent is provided with wipers for wiping the toe-end portion of an upper heightwise of a last and then inwardly over an insole on the last, and also with grippers for applying a pull to the toe end of the upper and for controlling it during a portion of the wiping operation of the wipers. It has been proposed heretofore to use in this machine, instead of such grippers, a device having the function of what is commonly known as a retarder, the device being arranged to clamp the marginal portion of the upper outspread on the wipers and to cooperate with them in applying a pull to the upper while preventing the formation of any objectionable wrinkles in the course of the wiping operation. Such a disclosure is found in Letters Patent No. 2,303,342, granted on December 1, 1942, on an application of F. C. Eastman's. An object of the present invention is to provide improved means for thus controlling the upper in the toe-lasting operation.

When a shoe is presented to a machine of the illustrated type it has commonly been lasted, or at least pulled over and fastened to the insole and last, immediately behind its toe portion. Under these conditions the margin of the upper may be readily outspread over the wipers around the end and along portions of the sides of the toe, but cannot be so readily outspread in locations near the portions which have already been lasted or fastened by pulling-over tacks, especially when the wipers are spaced a substantial distance heightwise of the last from the edge of the insole as they are prior to the wiping of the upper heightwise of the last. On the other hand, it is desirable to apply a more effective pull to the upper at and near the end of the toe than in locations near the previously lasted or pulled-over portions. The present invention, in one aspect, accordingly provides a retarder which is controlled by the shoe in such manner as to cause it to assume a position inclined relatively to the shoe bottom for clamping the upper on the wipers first at the end of the toe, and which in the

course of the wiping of the upper heightwise of the last, i. e., the upwiping operation, approaches a position in substantially parallel relation to the shoe bottom to render it effective to clamp the upper on the wipers also at the sides of the toe. Since the portions of the upper at the sides of the toe adjacent to the previously lasted or pulled-over portions may be more readily clamped outspread on the wipers when the latter are near the edge of the insole than earlier in the upwiping operation, this permits the retarder to be extended as far as desired along the sides of the toe and thus to control in a sufficiently effective manner substantially the entire toe portion of the upper, the pull applied to the upper in the upwiping operation being especially effective at and near the end of the toe, as is desirable, and progressively less effective in locations approaching the portions already lasted or pulled over. For the purposes in view the construction herein shown comprises a substantially U-shaped retarder supported for tipping movement about an axis extending widthwise of the shoe and located substantially opposite the extreme toe end of the shoe bottom, the ends of the retarder comparatively remote from the end of the toe being arranged to be engaged by the shoe to tip it to a position inclined relatively to the shoe bottom as and for the purpose above described. A spring against the resistance of which the retarder is thus tipped serves thereafter to tip it reversely to a position substantially parallel to the shoe bottom in response to the wiping movement of the wipers heightwise of the last. By reason of the location of the above-mentioned axis this reverse tipping movement of the retarder causes it to have an outward wiping action on the upper at the end of the toe, thus affording better insurance that the upper will be clamped smoothly on the wipers.

The invention further provides a novel construction such that the retarder may be readily adjusted for use on shoes of different widths. In the construction shown the retarder comprises a pair of upper-clamping members each arranged to engage the upper along one side and part way around the end of the toe, the members being adjustable bodily toward or from each other widthwise of the last and being so controlled as to tip as a unit about the above-mentioned axis. A third upper-clamping member is arranged to bridge any space between the pair of members while maintaining them in fixed relation to each other with respect to such tipping movement. Convenient means also are provided for adjust-

ing the pair of members and for releasing them, if desired, to permit them to be detached from their support.

The invention also provides means whereby the closing force applied to the wipers to press them against the upper in the wiping of the upper heightwise of the last may be adjustably varied to compensate, for example, for variations in the upper-clamping force applied by the retarder. In the machine shown in the previously mentioned Letters Patent No. 2,160,846 the wipers are closed inwardly about the toe by an operating member movable lengthwise of the last and acting through comparatively light springs associated respectively with the different wipers to press them against the upper in the upwiping operation, this member being operated through other spring mechanism whereby greater closing force is applied to the wipers in wiping the upper inwardly over the insole and pressing it against a lip on the insole. When a retarder is provided, as herein shown, for clamping the upper on the wipers, the pressure of the retarder on the upper may, if it is great enough, prevent the above-mentioned light springs from pressing the wipers against the upper with sufficient force for the best results in the upwiping operation. In the construction herein shown, therefore, there are provided, in place of each of the light springs used heretofore, a pair of springs of different strengths, together with means for selectively rendering one or the other of the springs or both combined effective on the wiper associated therewith. Accordingly, if the means for controlling the retarder is adjusted, as it may be by mechanism provided for that purpose, to apply comparatively light or comparatively heavy clamping pressure to the upper as required by the character of the upper materials, a corresponding adjustment may be effected to insure that the wipers will be held with the proper pressure against the upper in the upwiping operation. It will be understood that with respect to some novel features of the means thus provided for varying the closing force applied to the wipers the invention is not limited to an organization having a retarder or in which the wipers perform an upwiping as well as an overwiping operation.

The above and other features of the invention, including novel means for adjusting the wipers for shoes of different widths and various novel details of construction and combinations of parts, will now be more particularly described with reference to the accompanying drawings and thereafter pointed out in the claims.

In the drawings,

Fig. 1 is a view mainly in right-hand side elevation, with parts in section, showing the upper portion of a machine constructed generally as disclosed in the previously mentioned Letters Patent No. 2,160,846 but modified for purposes of the present invention;

Fig. 2 is a sectional view on a larger scale showing more clearly certain parts shown in Fig. 1;

Fig. 3 shows a portion of the structure as viewed in the direction of the arrow III in Fig. 1;

Fig. 5 is a perspective view of certain parts shown in Fig. 4;

Fig. 6 is a section on the line VI—VI of Fig. 4;

Fig. 7 is a section on the line VII—VII of Fig. 4;

Fig. 8 is a view partly in right-hand side ele-

vation and partly in section, showing the retarder provided by this invention and the means for operating it, the parts being shown as they appear in relation to a shoe prior to the toe-lasting operation;

Fig. 9 shows the retarder and parts associated therewith in front elevation;

Fig. 10 is a section on the line X—X of Fig. 9;

Figs. 11, 12 and 13 are views similar to a portion of Fig. 8, showing the parts as they appear at different times in the lasting operation; and

Fig. 14 is mainly a plan view of the parts as they appear in Fig. 11.

In view of the disclosure in Letters Patent No. 2,160,846, the present description will be confined to such portions of the machine as it is necessary to refer to for an understanding of the invention. The shoe, herein shown as one of the welt type, is positioned for the toe-lasting operation by a member 2 (Fig. 8) which engages the bottom face of the insole and in the operation of the machine on a shoe of that type engages also the inner face of the lip of the insole around the end and along the sides of the toe. The member 2 is supported on the lower end of a rod 4 which is vertically adjustable by means of a hand wheel 6 (Fig. 1). After the shoe has been presented by the operator in engagement with the member 2, it is clamped against this member by a toe rest 8 which is moved upwardly into clamping position substantially at the beginning of the cycle of power operations of the machine. To assist in controlling the shoe there is also provided a heel rest 10 (Fig. 1) which is moved rearwardly into engagement with its heel-end face early in the cycle of operations. The machine is further provided with wipers 12 which, as heretofore, are advanced and closed to embrace the upper about the toe end of the last and are swung upwardly to wipe the upper heightwise of the last, after which they are further advanced and closed to wipe the marginal portion of the upper inwardly over the feather and against the lip of the insole, the lip being supported against the inward pressure of the wipers by the member 2. The means for thus operating the wipers will be more particularly hereinafter described.

In the machine herein shown, as in that shown in the previously mentioned Letters Patent No. 2,303,342, the grippers used heretofore in a machine of this type for controlling the upper in the toe-lasting operation are dispensed with. In place of such grippers the present invention provides a retarder 14, constructed as hereinafter described, for clamping the marginal portion of the toe end of the upper on the top faces of the wipers 12 to control the upper in the course of the wiping movements of the wipers. This retarder is supported, as also hereinafter more particularly described, on the lower end of a bar 16 which corresponds to the bar 34 shown in the last-mentioned Letters Patent for controlling a retarder which in that instance was supported independently of the bar. The bar 16 is operated and controlled by mechanism also constructed substantially as disclosed in said Letters Patent. This mechanism includes an arm 18 (Fig. 8) on which the bar 16 is pivotally mounted substantially midway between its upper and lower ends, the arm 18 being mounted to swing about a rockshaft 20 supported in bearings in a head casting 22 (Fig. 1) on the top of the frame of the machine. By swinging movements of the arm 18 the bar 16 is moved downwardly to carry the retarder 14 into upper-clamping position and

is later moved upwardly to return the retarder to its initial position. In these movements the bar 16 is further guided and controlled by an arm 24 which is pivotally connected to its upper end and is mounted for swinging movements on a lug 26 formed on a plate 28 (Fig. 1) which is secured to the head casting 22. Integral with the arm 18 is another arm 30 adjustably connected by a spindle 32 to an arm 34 which is integral with the upper part 36 of a two-part clamp 38 embracing a friction ring 40 on the rockshaft 20, the ring being held in fixed relation to the rockshaft by a pin 42 threaded in the shaft and extending through a hole in the ring. The clamp 38 has a lower part 44 connected to the upper part 36 by a link 46. Pivotally mounted at one end on the upper part 36 is a lever 48 connected midway between its ends to the lower part 44 by a link 50. The other end of the lever 48 is connected to the lower end of a spring 52 the upper end of which is connected to one arm of a lever 54 (Fig. 3) pivotally mounted at 56 on the plate 28. By swinging this lever the tension of the spring 52 may be varied, the lever being provided with a spring-controlled pin 58 arranged to enter any one of a plurality of holes 60 in the plate 28 to hold the lever in adjusted position. It will be evident that the spring 52 tends by its action on the lever 48 and the link 50 to tighten the two-part clamp 38 on the friction ring 40 and also to turn the clamp about the axis of the rockshaft 20 and thereby to move the bar 16 downwardly. Initially, however, such turning of the clamp is prevented by engagement of the pin 42 with a shoulder 62 on the lower part 44 of the clamp, as shown in Fig. 8, the bar 16 and the retarder being held by the pin in an upraised position. It is only, therefore, in response to turning movement of the rockshaft 20 in a counterclockwise direction, as the parts are viewed in Fig. 8, that the spring 52 is permitted to impart downward movement to the bar 16. The rockshaft is automatically controlled in the power operation of the machine by a cam 64 (Fig. 1) the periphery of which engages a roll 66 mounted on one arm of a bell-crank lever 68 the other arm of which is connected by a link 70 to an arm 72 fast on the rockshaft 20. A spring 74 connected to the bell-crank lever 68 holds the roll 66 at all times in engagement with the cam 64 and serves when permitted by the cam to turn the rockshaft 20 in the above-mentioned counterclockwise direction.

The timing of the movements of the bar 16 relatively to the movements of the wipers may be assumed to be the same as disclosed in Letters Patent No. 2,303,342 with reference to the bar 34 therein shown, although the invention is not thus limited. Accordingly, the downward movement of the bar to carry the retarder into position for clamping the upper on the wipers takes place prior to the effective upwiping action of the wipers on the toe end of the upper. After the wipers in their upward movement have arrived in position to clamp the upper against the retarder, they cooperate with the retarder as they are moved farther upwardly to apply a pull to the upper as it is being wiped heightwise of the last, the margin of the upper slipping more or less between the wipers and the retarder. In this operation the bar 16 is lifted by the pressure of the upper on the retarder, causing the clamp 38 to turn about the friction ring 40 against the resistance of the spring 52, this movement of

the clamp being permitted by a slot 76 provided therein through which the pin 42 extends. It will be evident that in this operation the friction between the clamp and the ring 40 supplements the force of the spring 52 in resisting the upward movement of the bar 16 and therefore increases the force with which the retarder is pressed on the upper. When the wipers have nearly arrived at the limit of their upwiping movement, as illustrated in Fig. 12, the cam 64 begins to turn the rockshaft 20 in a clockwise direction, causing the ring 40 by frictional engagement with the clamp 38 partially to counteract the force of the spring 52 and thus to reduce the pressure of the retarder on the upper, the reduced pressure being continued as the wipers begin to wipe the margin of the upper inwardly. Preferably before the wipers have completed their inward wiping movements the pin 42 arrives in position again to engage the shoulder 62 of the clamp 38 and then acts positively on the clamp to lift the bar 16 (Fig. 13) and thus to carry the retarder away from the upper.

Reference has been made to the fact that the arm 30 connected to the bar 16 is adjustably connected by the spindle 32 to the arm 34 of the clamp 38. This spindle is swiveled in a trunnion block 78 pivotally mounted on the arm 30 and is threaded in a trunnion block 80 pivotally mounted on the arm 34. Accordingly, turning of the spindle by means of a hand wheel 82 thereon serves to swing the arms 30 and 18 and thus to lower or raise the bar 16 and the retarder while the clamp 38 is stationary. The purpose and effect of such an adjustment is to vary the length of time in the lasting operation that the retarder 14 clamps the upper on the wipers. If the retarder is adjusted, for example, in a downward direction, it will be moved to a lower position in response to the first turning movement of the rockshaft 20 and will accordingly clamp the upper on the wipers a greater length of time in the upwiping operation. The bar 16, therefore, will be lifted a greater distance in the upwiping operation and the shoulder 62 will be carried farther away from the pin 42 than if such an adjustment had not been made. By reason of the greater space thus provided between the shoulder and the pin, the rockshaft 20 will thereafter have to move farther in a clockwise direction before the pin meets the shoulder and accordingly the lifting of the retarder to release the clamping pressure on the upper will take place later in the course of the inward wiping movements of the wipers than if the adjustment had not been made. Conversely, an adjustment of the retarder in an upward direction will serve to reduce the length of time that it is pressed on the upper in both the upwiping and overwiping operations.

The retarder 14 herein shown is a substantially U-shaped retarder for clamping the upper around the end and along the sides of the toe. It includes a pair of upper-clamping members 84 each formed to engage the upper along one side and 65 part way around the end of the toe, these two members being adjustable bodily toward or from each other along a rod 86 which is fastened by a set screw 88 in the lower end of the bar 16 and is located substantially opposite the extreme toe end of the shoe bottom when the retarder is operating on the upper. The retarder further includes a central upper-clamping member 90 arranged to bridge any space between the two members 84 at the end of the toe, the member 90 being provided with flanges 92 (Fig. 9) whereby

it is mounted on the rod 86. The member 90 overlaps flat faces on the members 84 and, accordingly, the several members are held in fixed relation to one another with respect to movement about the rod 86, the members being thus movable as a unit in the operation of the machine as more particularly hereinafter explained. A spring 94 connected to a lug on the member 90 and to a pin 96 on the bar 16 tends to swing the retarder in a counterclockwise direction (Fig. 8) about the rod 86 and holds it initially in a position determined by engagement of the member 90 with a shoulder 91 on the lower end of the bar. For adjusting the members 84 toward or from each other there are provided blocks 98 associated respectively with the different members, these blocks being slidably movable in directions widthwise of the shoe in guideways provided by flanges 100 extending from opposite sides of the bar 16. Mounted to turn in bearings in the bar and in L-shaped members 101 secured to the flanges 100 between the flanges are spindles 102 having threaded portions engaging corresponding screw threads in the blocks 98 and having hand wheels 104 on their outer ends for turning them. Each block 98 carries a spring-controlled latch 106 arranged to extend normally into a groove 108 in the corresponding retarder member 84 but movable to release the member and thus to permit it to be readily detached from the rod 86, so that differently formed retarder members may be conveniently substituted for shoes of different shapes. It will be understood that the latch 106 serves as a connection between the block 98 and the retarder member 84 associated therewith for adjusting the member in response to turning movement of the corresponding spindle 102. It will be evident that the two retarder members 84 may be adjusted each independently of the other to position them in proper relation to a shoe of a given style and size.

In accordance with one of the objects of the present invention the members 84 herein shown are so shaped and are so adjusted relatively to each other that when the retarder is moved downwardly toward the wipers as hereinbefore described the end portions thereof which are comparatively remote from the end of the toe of the shoe are engaged by the insole, as illustrated in Figs. 11 and 14, so that the shoe causes the retarder to tip about the rod 86 against the resistance of the spring 94 into a position inclined relatively to the shoe bottom and thus to clamp the upper on the wipers first at the end of the toe where its marginal portion may be readily outspread over the wipers. Thereafter, in response to the upwiping movement of the wipers the spring 94 serves to tip the retarder reversely about the rod 86, as permitted by the shoe, until the retarder is in substantially parallel relation to the shoe bottom and thus clamps the upper on the wipers along the sides of the toe as well as at the end of the toe, as illustrated in Fig. 12. An especially effective pull, therefore, is applied to the portions of the upper around the end of the toe, as is desirable, and a less effective pull, near the end of the upwiping operation, in locations at the sides of the toe near the portions which have already been lasted or pulled over, in which locations the margin of the upper cannot be so readily outspread over the wipers until the latter are near the edge of the insole. It will be understood that as the wipers wipe the upper inwardly over the insole the retarder is effective to control it all around the toe until it

is lifted (Fig. 13) to release the upper from the clamping pressure.

A further advantageous characteristic of the construction above described is that as the retarder is tipped reversely by the spring 94 in the upwiping operation it has an outward wiping action on the marginal portion of the upper over the wipers at the end of the toe, as will be evident from a comparison of Figs. 11 and 12. This action of the retarder, which is due to the relation of the axis of the rod 86 to the upper-engaging portion of the retarder at the end of the toe, affords better insurance that the upper will be clamped in a smoothly outspread condition on the wipers.

As disclosed in Letters Patent No. 2,160,846, the wipers 12 are mounted on wiper holders 110 which are supported and guided for swinging or closing movements laterally of the shoe on a wiper carrier 112 under a cover plate 114 on the carrier. The wiper carrier is supported for movements to advance and retract the wipers lengthwise of the shoe on a pair of links 116, only one of which is herein shown, pivotally connected at their upper ends to the carrier near the front end of the latter, and also on the upper end of a lever 118 fulcrumed at 120 between its upper and lower ends and operated by a cam (not shown). The links 116 are connected at their lower ends to arms 122 fast on a rockshaft 124 on which also is secured a cam-operated arm 126 for swinging the wiper carrier 112 upwardly about its connection with the lever 118 to cause the wipers to wipe the upper heightwise of the last. In time relation to their advancing movements lengthwise of the shoe by the wiper carrier 112 and in the course of such movements the wipers are closed inward laterally of the shoe, first to engage the upper in the upwiping operation and thereafter to wipe it inwardly over the insole, by forward rectilinear movement of a slide 128 guided on the wiper carrier 112 and connected to the wiper holders 110 by means hereinafter described. For operating the slide 128 there is provided a rod 130 the front end of which is connected to the slide as hereinbefore described, and mounted on this rod is a sleeve 132 abutting at its front end against a flange 134 on the rod and having threaded thereon nuts 136 which provide an abutment for a washer 138. This washer is engaged by the front ends of two springs 140 and 142, of which the spring 142 is the stronger, the springs abutting respectively at their rear ends against rings 144 and 146. Secured to the ring 144 are a plurality of pins 148 and secured to the ring 146 are a plurality of pins 150, all these pins extending rearwardly through holes in a flange 152 integral with the sleeve 132 at the rear end of the sleeve. The pins 148 are arranged to aline with holes 154, only one of which is shown, in a disk 156 opposite the rear ends of the pins when the disk and the sleeve 132 are in a certain adjusted relation, and the pins 150 are arranged to aline with other holes (not shown) in the disk when the disk and the sleeve are in another adjusted relation. When the parts are in still another adjusted relation all the pins are out of alinement with the holes in the disk. By forward movement of the disk 156, therefore, the wiper-closing slide 128 is operated through either of the springs 140 or 142, or through both springs combined, depending upon the adjusted relation of the disk and the sleeve 132. The disk 156 is slidably mounted on a sleeve 158 mounted on the rear end of the rod 130 and

is connected by pins 160 (Fig. 4) to a pair of links 162 which are pivotally connected at their front ends to the bifurcated upper end of an arm 164 of a bell-crank lever 166 pivotally mounted on the wiper carrier 112. Another arm 168 of this bell-crank lever is connected by a link 170 to an arm 172 fast on a rockshaft 174, and also fast on this rockshaft is a cam-operated arm 176. It will thus be seen that by movement of the bell-crank lever 166 the disk 156 is moved forwardly and operates through one or the other or both of the springs 140, 142 to impart wiper-closing movement to the slide 128, the spring or springs being intended to yield, not in the upwiping operation, but in response to resistance to the closing movements of the wipers in pressing the upper inwardly against the lip of the insole. The adjustment for rendering either or both of the springs effective is made by turning the sleeve 132 and the parts thereon to vary the relation of the pins 148 and 150 to the holes in the disk 156, the latter being held from turning by rolls 178 (Fig. 4) mounted on the pins 160 and supported in guideways 180 in the wiper carrier 112. For thus turning the sleeve 132 there is integral with the sleeve 158, which interlocks with the sleeve 132, a gear sector 182 engaged by a movable rack bar 184 (Fig. 4). This and other structural details of the wiper-operating means thus far described are more fully disclosed in the previously mentioned Letters Patent No. 2,160,846.

Wiper-closing force has been transmitted heretofore from an operating member corresponding to the slide 128 to the wiper holders 110 through comparatively light springs acting to press the wipers yieldingly against the upper in the upwiping operation, and associated with these springs have been parts which limited the yield of the springs and served to transmit force positively from the operating member to the wiper holders when the wipers were thereafter operated with greater force through one or the other or both of the springs 140, 142 to press the upper against the lip of the insole. As previously explained, the tension of the spring 52 may be varied by adjustment of the lever 54, thereby varying the force with which the upper is clamped on the wipers by the retarder 14 in accordance with the character of the upper materials. In order that the pressure thus applied to the upper by the retarder may not prevent the wipers from being pressed against the upper with sufficient force in the upwiping operation, the machine herein shown is provided, in further accordance with the present invention, with mechanisms of such construction for transmitting force from the slide 128 to the different wiper holders 110, respectively, that the closing force applied to the wipers in the upwiping operation may be varied. Each of these mechanisms includes a coupling member 186 pivotally mounted on the slide 128 and another coupling member 188 pivotally mounted on the corresponding wiper holder 110. Extending from the member 188 is a stem 190 a portion of which is housed within a sleeve 192 secured by a pin 194 to the other coupling member 186. This pin extends through a slot 196 in the stem 190 which permits the member 186 and the sleeve 192 to move relatively to the member 188 a distance limited by the pin and slot. Surrounding the sleeve 192 are two springs 198 and 200, of which the spring 200 is the stronger, both springs abutting at one end against the coupling member 186. The other end 75

of the spring 198 abuts against a disk 202 which is normally engaged by a flange 204 on the front end of the sleeve 192 to limit expansion of the spring. Formed on the disk 202 are two forwardly extending fingers 206 (Figs. 5 and 7) which, with the parts positioned as shown, are arranged to align with recesses 208 formed in a ring 210 mounted for turning movement on a diametrically enlarged portion of the stem 190 and abutting against a shoulder 212 on the coupling member 188. The front end of the spring 200 abuts against a disk 214 normally in engagement with a shoulder formed on an enlarged portion 215 of the sleeve 192, this disk being provided with two fingers 216 which extend forwardly through openings in the disk 202 and the flange 204 to positions substantially contiguous to the rear face of the ring 210. This ring is provided with recesses 218 which, with the parts positioned as shown, are out of alignment with the fingers 216. It will accordingly be seen that when forward movement is imparted to the wiper-closing slide 128 force will be transmitted from the coupling member 186 to the coupling member 188 through the spring 200 alone, since the fingers 216 will abut against the rear face of the ring 210 while the fingers 206 will enter the recesses 208 in the ring and cause the spring 198 to remain idle. The ring 210, however, may be turned to a position in which the ends of the fingers 206 will abut against it while the fingers 216 will align with the recesses 218, in which case wiper-closing force will be transmitted through the spring 198 alone, the spring 200 remaining idle. The ring 210 may be turned to still another position in which both pairs of fingers 206 and 216 will abut against the rear face of the ring, so that force will be transmitted through both the springs 198 and 200, as may be desirable in operating on especially heavy upper materials when the retarder 14 is pressed on the upper with comparatively heavy pressure. By the construction herein shown the two rings 210 of the spring mechanisms associated with the different wipers are arranged to be turned in unison to corresponding adjusted positions by means of a slide 220 (Figs. 4 and 6) movable in directions widthwise of the shoe in a guideway formed in the lower face of the cover plate 114. Formed in this slide are slots 222 into which extend pins 224 from the rings 210, the pins being tapered and extending somewhat loosely into the slots. Former in the slide 220 also is a recess 226 (Fig. 6) into which extends a pin 228 formed on a disk 230 which is itself formed on the lower end of a shaft 232 mounted to turn in the cover plate 114. Fast on the upper end of this shaft is a crank arm 234 by which the shaft may be turned to impart the required adjusting movements to the slide 220. A spring-pressed pin 236 in the crank arm 234, which may be lifted by means of a knob 238 on its upper end, is arranged to enter any one of three recesses 240 in the cover plate 114 to maintain the rings 210 in any one of the three adjusted positions above described. The slots 222 in the slide 220 extend in such directions that as wiper-closing movements are imparted to the wiper holders 110 no substantial change occurs in the positions of the rings 210 such as to alter materially the relation of their recesses 208 and 218 to the corresponding fingers 206 and 216. It will be understood that after the upwiping operation, when the wipers are further closed to wipe the upper inwardly over the insole and to press it against the lip of the insole, the pin-and-slot connections 194, 196 between the

coupling members 186 and the sleeves 192 serve to limit the yield of such of the springs 198, 200 as are in use, so that force is transmitted positively from the coupling members 186 to the members 188 when the wipers are forced with heavier pressure against the upper through one or the other or both of the springs 140, 142.

The connection between the wiper-closing slide 128 and the rod 130 which operates the slide is such, in the construction herein shown, that the wipers may be adjusted toward or from each other for shoes of different widths by adjusting the slide relatively to the rod through turning movement of the rod. For this purpose the rod has formed thereon a screw thread 242 (Fig. 2) engaging a corresponding thread in the slide and has fast on its front end a pinion 244 in engagement with an elongated pinion 246 provided with a stem 248 rotatable in a bearing in the slide. A spring clip 250 on the stem serves to maintain it in position in its bearing. Extending through a bore in the stem 248 is a rod 252 the front end of which is rotatably supported in a member 254 having a stem 256 extending downwardly into a hole in the wiper carrier 112. Formed in the rod 252 is a keyway 258 into which extends a key 260 carried by the stem 248. Fast on the rod 252 is a knurled hand wheel 262 extending upwardly through a slot 264 in the cover plate 114. The rod 252 is prevented from moving forward relatively to the wiper carrier 112 by engagement of the wheel 262 with the member 254, and it is prevented from moving rearwardly relatively to the wiper carrier by engagement of the wheel with the cover plate 114. The wheel has in its periphery a plurality of holes 266 into which a pin may be inserted, if desired, to assist in turning it. It will be understood that in response to such turning movement of the wheel 262 the rod 139 is turned to adjust the slide 128 forwardly or rearwardly, the elongated pinion 246 sliding along the rod 252 and maintaining at all times its engagement with the pinion 244, and that by such movement of the slide 128 the wipers are adjusted toward or from each other about the axis of their closing movements as required by the width of the shoe to be operated upon.

The manner of operation of the construction provided for purposes of this invention having already been fully explained, no further explanation thereof is necessary.

Having described the invention, what I claim as new and desire to secure by Letters Patent of the United States is:

1. In a lasting machine, wipers for wiping the toe-end portion of an upper on a last heightwise of the last and then inwardly over an insole on the last, and a retarder for clamping the upper on the wipers at the end and the sides of the toe, said retarder being arranged to be tipped by the shoe to a position inclined relatively to the shoe bottom for clamping the upper on the wipers first at the end of the toe and thereafter to be tipped reversely to a position substantially parallel to the shoe bottom in the wiping of the upper heightwise of the last to cause it to clamp the upper on the wipers also at the sides of the toe.

2. In a lasting machine, wipers for wiping the toe-end portion of an upper on a last heightwise of the last and then inwardly over an insole on the last, a retarder for clamping the upper on the wipers at the end and the sides of the toe, portions of said retarder comparatively remote from the end of the toe being arranged to be controlled by the shoe to tip the retarder to a

position inclined relatively to the shoe bottom for clamping the upper on the wipers first at the end of the toe, and means for thereafter tipping the retarder reversely to a position substantially parallel to the shoe bottom in the wiping of the upper heightwise of the last to cause it to clamp the upper on the wipers also at the sides of the toe.

3. In a lasting machine, wipers for wiping the toe-end portion of an upper on a last heightwise of the last and then inwardly over an insole on the last, a retarder for clamping the upper on the wipers at the end and the sides of the toe, a support for said retarder on which it is mounted for tipping movements about an axis extending widthwise of the shoe, portions of the retarder comparatively remote from the end of the toe being arranged to be engaged by the insole to tip the retarder about said axis to a position inclined relatively to the shoe bottom for clamping the upper on the wipers first at the end of the toe, and a spring for thereafter tipping the retarder reversely to a position substantially parallel to the shoe bottom in the wiping of the upper heightwise of the last to cause it to clamp the upper on the wipers also at the sides of the toe.

4. In a lasting machine, wipers for wiping the toe-end portion of an upper on a last heightwise of the last and then inwardly over an insole on the last, a substantially U-shaped retarder for clamping the upper on the wipers around the end and along the sides of the toe, a support for said retarder on which it is mounted for tipping movements about an axis extending widthwise of the shoe and located substantially opposite the extreme toe end of the shoe bottom, the end portions of said retarder comparatively remote from the end of the toe being arranged to be engaged by the shoe to tip the retarder about said axis to a position inclined relatively to the shoe bottom for clamping the upper on the wipers first at the end of the toe, and a spring for thereafter tipping the retarder reversely to a position substantially parallel to the shoe bottom in the wiping of the upper heightwise of the last to cause it to clamp the upper on the wipers also at the sides of the toe.

5. In a lasting machine, wipers movable to wipe the toe-end portion of an upper on a last heightwise of the last and then inwardly over an insole on the last, and a retarder for clamping the upper on the wipers at the end and the sides of the toe, said retarder being movable heightwise of the last toward the wipers into upper-clamping position and being thereafter reversely movable heightwise of the last in response to wiping movement of the wipers in that direction, the retarder being arranged to be tipped by the shoe to a position inclined relatively to the shoe bottom as it is thus moved toward the wipers to cause it to clamp the upper first at the end of the toe and thereafter to be tipped reversely to a position substantially parallel to the shoe bottom in response to the wiping movement of the wipers heightwise of the last.

6. In a lasting machine, wipers movable to wipe the toe-end portion of an upper on a last heightwise of the last and then inwardly over an insole on the last, a retarder for clamping the upper on the wipers at the end and the sides of the toe, said retarder being movable heightwise of the last toward the wipers into upper-clamping position and being thereafter reversely movable heightwise of the last in response to wiping movement of the wipers in that direction, por-

tions of the retarder comparatively remote from the end of the toe being arranged to be engaged by the insole to tip the retarder to a position inclined relatively to the shoe bottom as it is thus moved toward the wipers to cause it to clamp the upper first at the end of the toe, and a spring for tipping the retarder reversely to a position substantially parallel to the shoe bottom in response to the wiping movement of the wipers heightwise of the last.

7. In a lasting machine, wipers for wiping the toe-end portion of an upper on a last heightwise of the last and then inwardly over an insole on the last, a retarder for clamping the upper on the wipers at the end and the sides of the toe, and a support for said retarder movable to carry it bodily heightwise of the last toward the wipers in the course of the operation of the machine, the retarder being arranged to assume a position inclined relatively to the shoe bottom for clamping the upper on the wipers first at the end of the toe and being movable thereafter relatively to said support about an axis extending widthwise of the shoe to a position substantially parallel to the shoe bottom as the upper is wiped heightwise of the last by the wipers.

8. In a lasting machine, wipers movable to wipe the toe-end portion of an upper on a last heightwise of the last and then inwardly over an insole on the last, a retarder for clamping the upper on the wipers at the end and the sides of the toe, a support for said retarder movable to carry it heightwise of the last toward the wipers and on which it is mounted for tipping movements about an axis extending widthwise of the shoe, portions of the retarder being arranged to be engaged by the shoe to tip the retarder about said axis to a position inclined relatively to the shoe bottom as it is thus moved toward the wipers to cause it to clamp the upper first at the end of the toe, said support and retarder being reversely movable heightwise of the last in response to wiping movement of the wipers in that direction, and a spring for tipping the retarder reversely about said axis to a position substantially parallel to the shoe bottom as the upper is thus wiped heightwise of the last.

9. In a lasting machine, wipers for wiping the toe-end portion of an upper on a last heightwise of the last and then inwardly over an insole on the last, and a retarder for clamping the upper on the wipers to control it in the wiping operation, said retarder being movable about an axis extending widthwise of the last to wipe the upper at the end of the toe outwardly over the wipers as the upper is wiped heightwise of the last by the wipers.

10. In a lasting machine, wipers for wiping the toe-end portion of an upper on a last heightwise of the last and then inwardly over an insole on the last, a retarder for clamping the upper on the wipers at the end and the sides of the toe, and a support for said retarder on which it is mounted for tipping movement about an axis extending widthwise of the shoe to a position inclined relatively to the shoe bottom for clamping the upper on the wipers first at the end of the toe and for reverse tipping movement thereafter to a position substantially parallel to the shoe bottom as the upper is wiped heightwise of the last by the wipers, said axis being so located as to cause the retarder in its reverse tipping movement to wipe the upper at the end of the toe outwardly over the wipers.

11. In a lasting machine, wipers for wiping the

- toe-end portion of an upper on a last heightwise of the last and then inwardly over an insole on the last, and a retarder for clamping the upper on the wipers at the end and the sides of the toe, the retarder being arranged to assume a position inclined relatively to the shoe bottom for clamping the upper on the wipers first at the end of the toe and being movable thereafter about an axis extending widthwise of the shoe to a position substantially parallel to the shoe bottom as the upper is wiped heightwise of the last by the wipers, said axis being located substantially opposite the extreme toe end of the shoe bottom to cause the retarder in its movement toward parallel relation to the shoe bottom to have an outward wiping action on the upper at the end of the toe.
12. In a lasting machine, the combination with wipers for wiping the toe-end portion of an upper on a last into lasted position, of a retarder for clamping the upper on the wipers to control it in the wiping operation, said retarder comprising upper-clamping members relatively adjustable bodily widthwise of the last and each arranged to engage the upper along one side and part way around the end of the toe, means supporting said members for tipping movement about an axis extending widthwise of the last to positions in substantially parallel relation to the wipers in response to pressure of the wipers upon them, and means constraining said members to move as a unit about said axis.
13. In a lasting machine, the combination with wipers for wiping the toe-end portion of an upper on a last into lasted position, of a retarder for clamping the upper on the wipers to control it in the wiping operation, said retarder comprising upper-clamping members relatively adjustable bodily widthwise of the last, means supporting said members for tipping movement about an axis extending widthwise of the last, and means for holding said members in fixed relation to each other during any movement thereof about said axis.
14. In a lasting machine, the combination with wipers for wiping the toe-end portion of an upper on a last into lasted position, of a retarder for clamping the upper on the wipers to control it in the wiping operation, said retarder including a pair of upper-clamping members relatively adjustable bodily widthwise of the last, means supporting said members for tipping movement about an axis extending widthwise of the last, and another upper-clamping member mounted to tip with said pair of members while maintaining them in fixed relation to each other and arranged to bridge any space between said pair of members resulting from their relative adjustment.
15. In a lasting machine, the combination with wipers for wiping the toe-end portion of an upper on a last into lasted position, of a retarder for clamping the upper on the wipers to control it in the wiping operation, said retarder including a pair of upper-clamping members relatively adjustable bodily widthwise of the last, means supporting said members for tipping movement about an axis extending widthwise of the last, a central upper-clamping member mounted to tip with said pair of members and arranged to bridge any space between the latter resulting from their relative adjustment; and a spring tending to tip all said members in one direction.

about said axis by force applied to said central member.

16. In a lasting machine, the combination with wipers for wiping the toe-end portion of an upper on a last into lasted position, of a retarder for clamping the upper on the wipers to control it in the wiping operation, said retarder including a pair of upper-clamping members relatively adjustable rectilinearly widthwise of the last and each arranged to engage the upper along one side and part way around the end of the toe and also including another upper-clamping member arranged to bridge any space between said first-named members at the extreme end of the toe resulting from their relative adjustment.

17. In a lasting machine, the combination with wipers for wiping the toe-end portion of an upper on a last into lasted position, of a retarder for clamping the upper on the wipers to control it in the wiping operation, said retarder comprising a pair of upper-clamping members adjustable rectilinearly toward or from each other widthwise of the last and each arranged to engage the upper along one side and part way around the end of the toe, and screws associated respectively with said different members and rotatable thus to adjust them each independently of the other.

18. In a lasting machine, the combination with wipers for wiping the toe-end portion of an upper on a last into lasted position, of a retarder for clamping the upper on the wipers to control it in the wiping operation, a support for said retarder relatively to which it is movable about an axis extending widthwise of the last, the retarder comprising a pair of upper-clamping members adjustable toward or from each other widthwise of the last, and means on said support for thus adjusting said members, the members being movable as a unit about said axis relatively to said adjusting means.

19. In a lasting machine, the combination with wipers for wiping the toe-end portion of an upper on a last into lasted position, of a retarder for clamping the upper on the wipers to control it in the wiping operation, a support for said retarder relatively to which it is movable about an axis extending widthwise of the last, the retarder comprising a pair of upper-clamping members adjustable toward or from each other widthwise of the last, and screw-operated blocks on said support for thus adjusting said members, the members being movable about said axis relatively to said blocks.

20. In a lasting machine, the combination with wipers for wiping the toe-end portion of an upper on a last into lasted position, of a retarder for clamping the upper on the wipers to control it in the wiping operation, said retarder comprising a pair of upper-clamping members adjustable toward or from each other widthwise of the last, a support for said members relatively to which they are thus adjustable, and latches for detachably holding the members on said support in adjusted relation.

21. In a lasting machine, the combination with wipers for wiping the toe-end portion of an upper on a last into lasted position, of a retarder for clamping the upper on the wipers to control it in the wiping operation, said retarder comprising a pair of upper-clamping members adjustable toward or from each other widthwise of the last, a support for said members, screw-operated blocks on said support for thus adjusting said members,

and latches for detachably connecting the members to said blocks.

22. In a lasting machine, wipers for wiping the toe-end portion of an upper on a last heightwise of the last and then inwardly over an insole on the last, a retarder for clamping the upper on the wipers to control it as it is wiped heightwise of the last, means for adjustably varying the pressure of the retarder on the upper, and means for closing the wipers inwardly about the toe and for holding them pressed yieldingly against the upper while the upper is pressed thereon by the retarder in the wiping of the upper heightwise of the last, said wiper-closing means being adjustable to vary the force with which the wipers are thus pressed against the upper in the wiping of the upper heightwise of the last.

23. In a lasting machine, wipers for wiping the toe-end portion of an upper on a last heightwise of the last and then inwardly over an insole on the last, a retarder for clamping the upper on the wipers to control it as it is wiped heightwise of the last and inwardly over the insole, means for adjustably varying the pressure of the retarder on the upper, and mechanism for closing the wipers inwardly about the toe to press them yieldingly against the upper in the wiping of the upper heightwise of the last and to wipe the upper thereafter inwardly over the insole, said wiper-closing mechanism including spring means adjustable to vary the closing force thus applied to the wipers in the wiping of the upper heightwise of the last and additional spring means for thereafter applying greater force to the wipers in closing them inwardly over the insole.

24. In a lasting machine, wipers for wiping the toe-end portion of an upper on a last heightwise of the last and then inwardly over an insole on the last, a retarder for clamping the upper on the wipers to control it as it is wiped heightwise of the last, means for adjustably varying the pressure of the retarder on the upper, and means including spring mechanisms associated respectively with the different wipers for closing them inwardly about the toe and for holding them pressed yieldingly against the upper in the wiping of the upper heightwise of the last, said spring mechanisms being each adjustable to vary the force with which the wipers are thus pressed against the upper in the wiping of the upper heightwise of the last.

25. In a lasting machine, wipers for wiping the toe-end portion of an upper on a last heightwise of the last and then inwardly over an insole on the last, a retarder for clamping the upper on the wipers to control it as it is wiped heightwise of the last, means for adjustably varying the pressure of the retarder on the upper, an operating member movable lengthwise of the last to close the wipers inwardly about the toe, spring mechanisms for transmitting closing force from said member respectively to the different wipers to press them against the upper while the upper is pressed thereon by the retarder in the wiping of the upper heightwise of the last, and means for adjusting said spring mechanisms to vary the force thus applied to the wipers by said operating member.

26. In a lasting machine, wipers for wiping the toe-end portion of an upper on a last heightwise of the last and then inwardly over an insole on the last, a retarder for clamping the upper on the wipers with variably predetermined force as it is wiped heightwise of the last, a member movable lengthwise of the last to close the wipers in-

wardly about the toe, spring mechanisms for transmitting closing force from said member respectively to the different wipers to press them against the upper in the wiping of the upper heightwise of the last and for adjustably varying the force thus applied to the wipers, and means including additional spring mechanism for operating said member to close the wipers inwardly over the insole and for adjustably varying the force thus applied to the wipers in that operation.

27. In a lasting machine, wipers for wiping the toe-end portion of an upper on a last heightwise of the last and then inwardly over an insole on the last, a retarder for clamping the upper on the wipers with variably predetermined force as it is wiped heightwise of the last, and means including spring mechanisms associated respectively with the different wipers for closing them inwardly about the toe and for holding them pressed yieldingly against the upper in the wiping of the upper heightwise of the last, each of said spring mechanisms comprising a pair of springs of different strengths and means adjustable to render one or the other of said springs selectively effective on the wiper associated therewith.

28. In a lasting machine, wipers for wiping the toe-end portion of an upper on a last heightwise of the last and then inwardly over an insole on the last, a retarder for clamping the upper on the wipers with variably predetermined force as it is wiped heightwise of the last, and means including spring mechanisms associated respectively with the different wipers for closing them inwardly about the toe and for holding them pressed yieldingly against the upper in the wiping of the upper heightwise of the last, each of said spring mechanisms comprising a pair of springs of different strengths and means adjustable to render one or the other of said springs selectively effective on the wiper associated therewith.

29. In a lasting machine, wipers for wiping an end portion of an upper on a last into lasted position, means including spring mechanisms associated respectively with the different wipers for closing them inwardly widthwise of the last, each of said spring mechanisms being adjustable to vary the force applied to the wiper associated therewith, and a device common to both said spring mechanisms for thus adjusting them simultaneously.

30. In a lasting machine, wipers for wiping an end portion of an upper on a last into lasted position, an operating member movable lengthwise of the last to close the wipers inwardly widthwise of the last, spring mechanisms for transmitting closing force from said member respectively to the different wipers, each of said spring mechanisms including an adjusting member mounted for turning movement to vary the force applied by said operating member to the wiper associated therewith, and another member movable widthwise of the last for imparting such turning movements to both said adjusting members simultaneously.

31. In a lasting machine, wipers for wiping an end portion of an upper on a last into lasted position, a member movable lengthwise of the last to close the wipers inwardly widthwise of the last, spring mechanisms for transmitting closing force from said member respectively to the different wipers, each of said spring mechanisms including

a pair of springs of different strengths and an adjusting member movable to render one or the other of said springs selectively effective on the wiper associated therewith, and a device common to said adjusting members for moving them simultaneously.

32. In a lasting machine, wipers for wiping an end portion of an upper on a last into lasted position, a wiper carrier supporting said wipers and movable to advance them lengthwise of the last in operating on the upper, means supported on said wiper carrier for closing the wipers inwardly widthwise of the last, said wiper-closing means including a pair of connected members movable lengthwise of the last relatively to the wiper carrier and operated one by the other thus to close both the wipers, means for thus operating said other member in the course of the wiper-advancing movement of the wiper carrier but independently of that movement, and means wholly supported on said wiper carrier for effecting relative adjustment of said members to adjust the wipers toward or from each other widthwise of the last.

33. In a lasting machine, wipers for wiping an end portion of an upper on a last into lasted position, a wiper carrier supporting said wipers and movable to advance them lengthwise of the last, a member supported on said wiper carrier and rectilinearly movable relatively to the carrier lengthwise of the last to close the wipers inwardly widthwise of the last, a rod threaded in said member and movable lengthwise thus to operate the member in the course of the wiper-advancing movement of the wiper carrier but independently of that movement, and means wholly supported by said wiper carrier for turning said rod to adjust said member and thereby to adjust the wipers toward or from each other widthwise of the last.

34. In a lasting machine, wipers for wiping an end portion of an upper on a last into lasted position, a wiper carrier supporting said wipers and movable to advance them lengthwise of the last, means supported on said wiper carrier for closing the wipers inwardly widthwise of the last, said wiper-closing means including a pair of connected members movable lengthwise of the last relatively to the wiper carrier and operated one by the other thus to close both the wipers, said members being relatively adjustable by rotation of one of them relatively to the other to adjust the wipers toward or from each other widthwise of the last, and means including gearing supported on said wiper carrier for turning said rotatable member.

35. In a lasting machine, wipers for wiping an end portion of an upper on a last into lasted position, a wiper carrier supporting said wipers and movable to advance them lengthwise of the last, said wiper carrier having a cover plate thereon, means supported on said wiper carrier for closing the wipers inwardly widthwise of the last, said wiper-closing means including a pair of connected members movable lengthwise of the last relatively to the wiper carrier and operated one by the other thus to close both the wipers, and means including a rotatable member extending through an opening in said cover plate into position for use by the operator for effecting relative adjustment of said connected members to adjust the wipers toward or from each other widthwise of the last.

PHILIP E. BURBY.
